(57) **CLAIM**

The ornamental design for a belt adjusting member, as shown and described.

DESCRIPTION

FIG. 1 is a front view of a belt adjusting member showing my new design;

FIG. 2 is a rear view thereof;

FIG. 3 is a right side view thereof, the left side being symmetrical to the right side view;

FIG. 4 is a top plan view thereof;

FIG. 5 is a bottom plan view thereof;

FIG. 6 is a cross sectional view taken along line 6—6 in FIG. 1;

FIG. 7 is a cross sectional view taken along line 7—7 in FIG. 1; and,

FIG. 8 is a cross sectional view thereof as in FIG. 7, in a condition that the belt adjusting member is in use.

It being understood that the broken lines are for illustrative purposes only.
